FIG. 1

FIG. 2

INVENTOR

George D. Sailer
By Kay Intra
a/c

UNITED STATES PATENT OFFICE.

GEORGE D. SAILER, OF JEANNETTE, PENNSYLVANIA, ASSIGNOR TO MCKEE GLASS COMPANY, OF JEANNETTE, PENNSYLVANIA, A CORPORATION OF PENNSYLVANIA.

DESIGN FOR A TRANSPARENT GLASS DISH.

58,201.

Specification for Design. Patented June 21, 1921.

Application filed November 8, 1920. Serial No. 422,742. Term of patent 14 years.

To all whom it may concern:

Be it known that I, GEORGE D. SAILER, a citizen of the United States, residing at Jeannette, in the county of Westmoreland, State of Pennsylvania, have invented a new, original, and ornamental Design for a Transparent Glass Dish, of which the following is a specification, reference being had to the accompanying drawing, forming a part thereof.

Figure 1 is a perspective view of a transparent glass-dish showing my new design, and Fig. 2 is a horizontal section.

The important feature of my design consists in the formation of panels on the inside of a transparent dish of any shape, the said panels giving a peculiar optical effect due to the transparency of the glass.

I claim:

The ornamental design for a transparent glass dish as shown.

GEORGE D. SAILER.
